UNITED STATES PATENT OFFICE.

MILTON C. HUGHES, OF ROY, WASHINGTON.

PIE-CUTTING GUIDE.

Application filed June 24, 1926. Serial No. 118,340.

This invention relates to means for indicating the manner in which a pie may be divided in order to secure any desired number of segments or pieces, and the general object of my invention is to provide a very simple device of this character which may be readily used with pies of any diameter and which will accurately indicate the manner in which the pie may be divided to divide it into three, four, five or even nine pieces or segments.

Another object is to provide a device of this character which is adapted to be used to simply indicate the point from which a radial cut may be made or which may be provided with a guide or a cutting knife.

My invention is illustrated in the accompanying drawings wherein:—

Figure 1 is a top plan view of a pie cutting guide constructed in accordance with my invention;

Fig. 2 is a section on the line 2—2 of Figure 1.

Referring to these drawings 10 designates an annulus which may be made of any suitable material and which may be either transversely flat or formed as shown in Figure 2 with an upstanding flange 11. This ring 10 is sufficiently wide to carry upon it certain characters as will be later referred to and is preferably formed at three or more points with inwardly projecting tongues 12 adapted to rest upon the upper face of the pie to be cut and preferably disposed equidistantly around the ring 10. One edge 13 of each tongue is disposed on a radial line which will intersect at the center of the pie, assuming that the ring 10 is disposed concentric to said center. Adjacent one of these tongues the ring 10 may carry the letter "S" indicating that this tongue is the starting point for cutting the pie.

At suitable points around the ring 10 indicating indicia will be provided designated 14, from which points cuts may be made to the center of the pie and I have illustrated this indicating indicia being so disposed as to indicate how the pie may be divided into three, four, five, six, seven, eight or nine pieces. It will be obvious that the three projecting tongues will indicate how the pie may be divided into three segments. It will be seen, of course, that the indicating marks for dividing the pie into four segments will also be used for dividing the pie into eight segments and that certain of the indicating

marks for dividing the pie into four or eight segments will also be used for dividing it into six segments and certain of the marks for indicating how the pie may be divided into three segments will be used for dividing it into six segments and also into nine segments.

Preferably a guide will be used with this ring 10, this guide having three or more arms designated 15 meeting at a central point, the edge of one of these arms being radial to the ring 10 and this edge being used for cutting purposes, that is to guide the cutting knife.

In case the guide 15 is used the ring 10 is provided with the flange 11 as heretofore stated, and this flange 11 will cause the knife guide 15 to be always disposed concentrically to the ring. The tongues 12 rest upon the face of the pipe and thus support the ring in case the pie is smaller in diameter than the diameter of the ring 10. These tongues are provided with graduations 13 so that the ring may be centered upon the pie. Thus, if the circumference of the pie is disposed at the same graduation on each of the tongues 12, it will, of course, follow that the ring will be concentric to the pie. In the use of this device the ring 10 is laid on the pie and centered so that an equal margin will show all around the pie. The pie is then cut from the center to the figure which indicates the number of pieces into which the pie is to be cut, the first cut being made from the center to the starting point S and subsequent cuts being made from the center to the figures denoting the number of pieces into which the pie is to be cut.

I claim:—

1. A pie cutting guide comprising a ring adapted to be centered upon a pie and having spaced indications on its margin of the number of cuts to be made from the indications to the center of the pie in order to cut any desired number of pieces or segments, said ring having inwardly projecting tongues adapted to rest upon the upper surface of a pie and spaced equidistantly from each other.

2. A pie cutting guide comprising a ring adapted to be centered upon a pie and having spaced indications on its margin of the number of cuts to be made from the indications to the center of the pie in order to cut any desired number of pieces or segments, the ring having an upturned margin,

and a cutting guide having a plurality of arms radiating from a common center and supported by said flange in centered relation to the ring, one of said arms constituting a straight edge for the guidance of a knife.

3. A pie cutting guide comprising an annular member adapted to be centered upon a pie and having spaced indications on its margin of the number of cuts to be made from the indications to the center of the pie in order to cut any desired number of pieces or segments, and a cutting guide rest-

ing upon the ring and extending across the same and having a straight edge intersecting the center of the annular member and constituting an edge for the guidance of a knife, the annular member and the cutting guide having coacting means to maintain the straight edge of the cutting guide in a position where it will intersect the center of the annular member.

In testimony whereof I hereunto affix my signature.

MILTON C. HUGHES.
